FIRE-EXTINGUISHING COMPOSITIONS

Jesse O. Reed, Washington, D. C.

No Drawing. Application April 10, 1936, Serial
No. 73,723

11 Claims. (Cl. 23—8)

(Granted under the act of March 3, 1883, as
amended April 30, 1928; 370 O. G. 757)

This application is made under the act of March 3, 1883, as amended by the act of April 30, 1928, and the invention described herein, if patented, may be manufactured and used by or 5 for the Government for governmental purposes without the payment to me of any royalty thereon.

This invention relates to an improvement in fire-extinguishing compositions and particularly 10 to the inclusion in such compositions of a material that greatly increases their effectiveness.

The principles of this invention are applicable to almost every type of fire-extinguishing composition and for that reason it may be well, at the 15 outset, to describe briefly the more important types of extinguishing compositions. All of these compositions operate on the same principle, that is, of covering the fire with an inert material, either solid, liquid, vapor, or gas, which excludes air and thus smothers the flame.

One class of compositions consists of materials 20 adapted to be applied directly to the flame. Such material may be a liquid, such as carbontetrachloride, or a powder, containing sodium bicarbonate, sodium borate, boric acid, ammonium phosphate, sand, ashes, infusorial earth, mica, asbestos, talc or other materials, in various combinations or proportions.

Another kind of fire-extinguishing composition 25 consists of two or more materials that upon the mixing will form a gas or foam which may be released upon the fire. The ordinary soda-acid extinguisher and the extinguisher that depends for its action upon sodium bicarbonate, aluminum sulphate and a foam stabilizer such as licorice extract, use this type of composition.

According to the present invention any of the fire-extinguishing compositions described may be improved and made much more effective by the 30 addition thereto of chlorinated organic materials of a resinous nature. The materials that have been found best suited for this purpose are chlorinated rubber, chlorinated petroleum derivatives, chlorinated vinyl resin and chlorinated turpentine. The degree of chlorination does not appear to be highly critical. Rubber chlorinated to the extent of around 70%, vinyl resin about 40% chlorinated, paraffin about 60% chlorinated and rosin chlorinated to the extent of around 55%, 35 all appear to be satisfactory. Various percentages of chlorinated material may be used in the compositions. It has been found that around 15% is preferable.

The reason for the increased effectiveness of 40 the compositions including the chlorinated resin-

ous compounds is not entirely understood, but the effect is evident upon comparison of the extinguishing compositions with and without the chlorinated material added and it seems that the chlorinated products may either reduce the 5 volatility of the liquids present, aid in covering the flame, or yield, upon heating, products that tend to smother the fire. Particularly after the fire has once begun to subside does the new composition appear to be of particular advantage, 10 because it thoroughly completes the job of extinguishing the fire instead of rapidly vaporizing and allowing the fire to start over again.

In order that the present invention may be more 15 thoroughly understood, the following may be given as formulas for fire-extinguishing compositions embodying the principles of this invention:

DRY POWDER EXTINGUISHING COMPOSITION	
	Percent
Chlorinated vinyl resin	15
Sodium bicarbonate	60
Sodium borate	15
Boric acid	5
Silica	25

FLUID EXTINGUISHING COMPOSITION	
	Percent
Carbontetrachloride	90
Chlorinated paraffin	10

Two-SOLUTION EXTINGUISHING COMPOSITION	
Solution 1	Percent
Sodium bicarbonate	20
Sulfonated lauryl alcohol	3
Chlorinated rubber	20
Water	57

Solution 2	Percent
Concentrated sulphuric acid	100

The above examples of compositions illustrate the principles of this invention but it is to be understood that they are not the only ways that the principles may be applied. For example, the resinous materials may be added to the water in a hose stream or in a sprinkler system or in a fire department pumper, and many other formulas 45 for fire-extinguishing compositions including the chlorinated materials may be easily devised.

In incorporating the chlorinated materials, they may be merely mixed in powder form with other dry materials, they may be stirred into 50

liquids immediately before use, particularly in the case of their use with water, they may be dissolved, as in carbontetrachloride, or they may be emulsified with the other materials.

5 Having thus described my invention, what I desire to secure by Letters Patent is:

1. A composition for extinguishing fires that includes a material for smothering the fire and a stable, non-volatile chlorinated organic material of relatively high molecular weight.

10 2. A composition for extinguishing fires that includes a material for smothering the fire and a stable, non-volatile chlorinated resinous organic material.

15 3. A composition for extinguishing fires that includes a material for smothering the fire and chlorinated paraffin.

20 4. A composition for extinguishing fires that includes a material for smothering the fire and chlorinated rubber.

25 5. An improvement in fire-extinguishing compositions that comprises including in the composition a stable, non-volatile chlorinated organic material of relatively high molecular weight.

6. A composition for extinguishing fires that comprises a non-inflammable liquid and a stable,

non-volatile chlorinated organic material of relatively high molecular weight.

7. A composition for extinguishing fires that comprises carbontetrachloride and a stable, non-volatile chlorinated organic material of relatively high molecular weight.

10 8. A composition for extinguishing fires that comprises water and a stable, non-volatile chlorinated organic material of relatively high molecular weight.

15 9. A composition for extinguishing fires that comprises a plurality of materials that will react to form a gas and a stable, non-volatile chlorinated organic material of relatively high molecular weight.

20 10. A composition for extinguishing fires that comprises a plurality of materials that will react to form a foam and a stable, non-volatile chlorinated organic material of relatively high molecular weight.

25 11. A composition for extinguishing fires that includes around 85% of a material for smothering the fire and around 15% of a stable, non-volatile chlorinated organic material of relatively high molecular weight.

JESSE O. REED.
